UNITED STATES PATENT OFFICE.

WILLIAM LORD BLISS, OF BROOKLYN, NEW YORK.

ELECTRICAL APPARATUS.

1,022,058.

Specification of Letters Patent.

Patented Apr. 2, 1912.

Application filed November 1, 1906. Serial No. 341,534.

To all whom it may concern:

Be it known that I, WILLIAM LORD BLISS, a citizen of the United States, residing at Brooklyn, county of Kings, New York, have 5 invented certain new and useful Improvements in Electrical Apparatus, of which the following is a full, clear, and exact description.

My invention relates to improvements in 10 apparatus for incandescent electric lighting.

The invention is directed to what are commonly known as multiple filament or turn-down lamps. In multiple filament lamps the luminosity is controlled by circuit 15 conditions. The lamp of my invention is adapted to either alternating or direct current circuits, and it is possible to control a plurality by the same instrumentality and from a distant point, if desired.

20 Figure 1 is a diagrammatic view of a system and apparatus embodying my invention, Fig. 2 is a side view of a lamp and vertical sectional view and side elevation of a socket and lamp with conductors embodying 25 my invention, Fig. 3 is a detail view, showing one form of switch for use in the system, the connections being such as to cause the maximum luminosity of the lamp or lamps in circuit. Fig. 4 is a similar view, the circuit being open so that the lamp or lamps will be "out". Fig. 5 is a similar view, but showing the connections such that the lamp or lamps will be giving minimum luminosity.

35 1 indicates the lamp bulb containing the high resistance filament 2 and the low resistance filament 3. This bulb has a suitable insulating base. One end of the filament 3 is connected to the externally screw-threaded 40 metallic annular terminal 4. One end of the filament 2 is connected to the central metallic disk terminal 5. Both filaments are also connected to the intermediate metallic annular terminal 6. The bulb 1 together 45 with its filaments 2 and 3 and their terminals 4, 5 and 6 constitute the lamp.

The socket member has a screw-threaded terminal 7 and spring arm terminals 8 and 9 mounted on the insulating base 10 and 50 adapted to form electrical connections with the lamp terminals 4, 5 and 6, respectively.

55 11 is a frame mounted in the insulating base 10 and carrying the rotatable switch member 12, handle 13, and spring 14.

55 The socket has a suitable covering 15 and suitable insulation on its interior, as is cus-

tomary in socket construction. The conductor for the socket is composed of the three insulated wire members *o*, *i* and *c*, which are preferably braided together and connected respectively to the threaded terminal 7 and the spring terminals 8 and 9. It will thus be seen that when the lamp is in the socket, the wires *o*, *i* and *c* are connected respectively to the outer terminal 4 for the low 60 resistance filament 3, the inner terminal 5 of the high resistance filament 2, and the intermediate terminal 6 common to both filaments. The circuit from wire *o* to the outer terminal 7 passes through the frame 11 and 70 switch member 12, so that the circuit may be opened and closed in the socket.

X and Y indicate the mains of a generating circuit.

The three distributing wires *o*, *i* and *c* 75 may be connected to one or more lamps, as shown in the diagram of Fig. 1. The connections between the generating and distributing circuits is under the control of a suitable device. Fig. 1 shows the controller in 80 its simplest form, in which it consists of the movable switch arm 16 connected to main X, and two stationary contacts 17 and 18 connected to the branch distributing wires *i* 85 and *c* respectively. The main Y is connected direct to the distributing branch *o*.

In the position of the controller shown in 90 Fig. 1, current will pass from the main X through switch arm 16, contact 17, distributing branch *i*, thence to the inner terminal and high resistance filament of each lamp in circuit, thence to the low resistance filament of each lamp in circuit, and back through the outer terminal of each lamp and through the distributing branch *o* 95 to the main Y. This position may be called the series position for both filaments in each lamp, and is indicated by the arrow S. When the filaments are in series, the potential drop in each is proportional to its resistance. The resistance of the filaments is designed so that under the voltage available in the system the high resistance filament in the series arrangement will receive sufficient current to heat it to incandescence. Under these conditions the proportion of current available for the low resistance filament is insufficient to heat it to incandescence, the lamp is accordingly lighted, but 100 "turned down" or "dim." When the switch arm is in position opposite the arrow P, two filaments of each lamp are thrown in 105 110

parallel, so that in effect the high resistance filament 2 of each lamp is short-circuited by the switch arm bridging the contact plates 17 and 18 of the controller. In this 5 position, the effect of the high resistance filament 2 is practically negligible so that the low resistance filament 3 will receive substantially the entire current and become 10 luminous, and the lamp or lamps will be "turned up" or "bright."

The controller of Fig. 1 may be considered as a simplified illustration of the preferred form shown in Figs. 3, 4 and 5. This preferred form is adapted to be turned 15 on low, off, on high, off, etc., by continued rotation step by step, one-eighth of a turn for each change. This is particularly adapted for snap switches. Such a switch would have the main contacts 19 and 20 for 20 the generating circuit wires Y and X respectively, and the contacts 21, 22 and 23 for the distributing wires *i*, *c* and *o* respectively. The switch arms 24 and 25 are insulated from each other but mounted to 25 rotate together similar to the old style of switch arms in snap switch practice. When the parts are in the position shown in Fig. 3, the lamp or lamps in the distributing circuit will be turned on bright, the lower resistance filaments being incandescent, since the high resistance filament or filaments are short-circuited by a part of the switch arm 25. An eighth of a turn in a clockwise direction brings the parts into the position 30 shown in Fig. 4, when the circuits are open and the lamp or lamps out. Another eighth of a turn from the position shown in Fig. 4 and in a clockwise direction will bring the parts to the position shown in Fig. 5, in 35 which the high and low resistance filaments of the lamp or lamps are in series, and the high resistance filament incandescent and consequently on "dim." Another eighth of a turn in a clockwise direction from the position shown in Fig. 5, will throw the arm 40 24 off the contacts 20 and 21 and open the circuit to turn off the lamp or lamps.

The sockets are preferably constructed as shown in Fig. 2. In this it will be noted 50 that the terminals are so arranged that an ordinary single filament lamp having an outer screw-threaded terminal and an inner disk terminal may be inserted and turned on and off by means of the controller of my 55 invention. By the socket switch it is possible to turn each lamp independently on or off, as desired, at the lamp. The question whether the multiple filament lamp is to be "bright" or "dim" is, however, determined

60 by the controller and the circuit connections, which are otherwise supposed to be permanent. In the form in which the circuits are illustrated, a single filament lamp in one of my sockets will be turned on when the controller is in either the position shown 65 in Fig. 3 or in Fig. 5.

Ordinary single filament lamps, such as 70 26 and 27, may be connected in the same circuits with the multiple filament lamps between the conductor *o* and either conductor *i* or *c*, depending upon whether it is desired to have the single filament lamp lighted simultaneously with the "bright" 75 or "dim" lighting of the multiple filament lamps. Such a combination system makes 80 it possible to obtain novel and valuable lighting effects and preserve a good degree of regulation.

This apparatus and system has particular 85 utility wherever it is desirable to employ a plurality of lamps. By a single instrumentality it is thus possible to turn on a lamp or lamps either "bright" or "dim," or turn them off as desired.

The lamp of my invention may be used 85 in an ordinary so-called Edison socket having a central disk terminal and an outer screw-threaded terminal without any change or any adapter as is necessary with most 90 multiple filament lamps.

The advantages of the lamp are its simplicity, reliability and adaptability.

What I claim is:

1. An incandescent electric lighting apparatus, comprising a socket having three 95 terminals, a three-wire conductor connected to said terminals, a switch in said socket adapted to control the circuit to one of said terminals, and a removable bulb having a plurality of filaments of different resistances with fixed concentric terminals adapted to be connected to said socket terminals.

2. Incandescent electric lighting apparatus comprising a socket having a threaded terminal and two yielding terminals and a removable bulb member having two filaments, an exterior terminal for one filament, a central terminal for the other filament, one of said two latter terminals being threaded, and an annular terminal common to both filaments, the two yielding socket terminals engaging the annular bulb terminal and the non-threaded bulb terminal respectively.

WILLIAM LORD BLISS.
